(57) **CLAIM**

The ornamental design for an eye drop applicator, as shown and described.

DESCRIPTION

FIG. 1 is a perspective view of an eye drop applicator, shown with a removable cap.

FIG. 2 is a side view of the eye drop applicator of FIG. 1, shown with the cap positioned on the applicator.

FIG. 3 is a side view of the eye drop applicator of FIG. 1, shown without the cap, with other side views being identical to the side view shown in FIG. 3.

FIG. 4 is a top view of the eye drop applicator of FIG. 1, shown with the cap positioned on the applicator.

FIG. 5 is a top view of the eye drop applicator of FIG. 1, shown without the cap.

FIG. 6 is a bottom view of the eye drop applicator of FIG. 1, shown without the cap.

FIG. 7 is a side view of the eye drop applicator of FIG. 1, shown positioned on a bottle and with the cap positioned on the applicator; and,

FIG. 8 is a perspective view of the eye drop applicator of FIG. 1, shown without the cap and shown disposed on a user's finger, filled with an eye drop, and positioned with respect to a user's eye.

The dash-dot broken lines represent an unclaimed boundary of the claimed design. The remaining broken lines illustrate unclaimed subject matter and/or surrounding environment and form no part of the claimed design.

1 Claim, 8 Drawing Sheets
